CLOTHESLINE AND SUPPORT THEREFOR

Benjamin H. Sperber, Brooklyn, N. Y.

Application November 28, 1947, Serial No. 788,512

3 Claims. (Cl. 211—119.02)

1

This invention relates to improvements in clothesline holders including an improved clothesline pulley and attachment therefor.

The principal object of this invention is the provision of a clothesline holder which supports the clothesline in position transversely of the window frame through which clothes are hung, thereby enabling the housewife to hang clothes on the clothesline without bending out of the window. It is well known that it is quite dangerous to hang clothes on conventional clotheslines through upper story windows. Conventional clotheslines extend perpendicularly of the window frame, and it is necessary for the housewife hanging clothes on such conventional clotheslines to lean out of the window to a dangerous extent. Efforts have been made to rig up a clothesline system which would make the clothesline more accessible to the person hanging clothes thereon through a window. It is clear, however, that the means which have heretofore been devised to effect this result have been inadequate for the purpose intended and completely unsatisfactory, else they would long ago have replaced conventional clothesline systems and apparatus.

It is accordingly the principal object of this invention to provide a clothesline holder which would make the clothesline more accessible to a person hanging clothes thereon from inside the window of a house.

Another object of this invention is the provision of a new and improved arrangement for conventional clotheslines, whereby said clotheslines may be brought into a more accessible location with respect to a person hanging clothes thereon through a window.

Still another object of this invention is the provision of an improved type of clothesline pulley which is adapted to function in conjunction with conventional clothesline pulleys without removing said conventional pulleys from their present location and which in conjunction with said pulleys brings the clothesline into a more accessible location from the point of view of a person standing on the inside of the window to which said pulleys are attached.

Still a further object of this invention is the provision of an improved type of clothesline pulley which may be mounted on a vertical axis and which is adapted to accommodate clothespins carried by the clothesline mounted thereon.

A still further object of this invention is the provision of a clothesline pulley of the character last described which includes a "pick-up" 55

2

feature enabling it to remain in unbroken contact with a sagging clothesline.

Preferred embodiments of this invention are shown in the accompanying drawing in which:

5 Fig. 1 is a side view of one of said embodiments, partly in section, on the line 1—1 of Fig. 2;

Fig. 2 is a top view thereof;

10 Fig. 3 is an enlarged top view of the improved type of pulley herein claimed and of the bracket which supports it;

Fig. 4 is a side view of said pulley and bracket; and

15 Fig. 5 is a cross sectional view through a modified form of such pulley.

Referring now to Figs. 1 and 2, it will be seen that a conventional clothesline pulley 10 is attached by means of a bracket 11 to one side 12 of the frame of a window 13. A second conventional pulley 15 is attached by means of hook 16 to a suitable support such as a pole 17. In conventional clothesline systems the clothesline 20 extends around pulley 10 to and around pulley 15 and back again to pulley 10. In conventional systems these pulleys are mounted on a pair of hooks such as hooks 16 and they rotate on substantially parallel horizontal axes. In conventional systems only two such pulleys are used, and it will be clear that under normal conditions, unless the clothesline twists or there is a strong wind, said pulleys are in substantial alignment with each other.

In the present system the two conventional pulleys 10 and 15 are brought into a different relationship with respect to each other and although pulley 15 remains mounted on a conventional hook 16, pulley 10 should preferably be mounted on a bracket such as bracket 11 which supports the pulley a predetermined distance away from the window frame.

40 A third pulley, to wit, pulley 25, the pulley herein claimed to be new, is brought into the clothesline system heretofore discussed. This pulley is mounted on a vertical axis, and it is supported by bracket 26 which is affixed to the other side 27 of the window frame. Immediately adjacent said pulley 25 is another pulley 28 which is of conventional construction but which, like pulley 25, is mounted on a vertical axis. It, too, is supported by means of bracket 26.

The two pulleys 25 and 28 last above mentioned occupy a position relative to pulleys 10 and 15 corresponding substantially to the position which the right angle occupies with respect to the other two angles of a right angle triangle.

It will be observed that the clothesline 20 is made to extend around the top of pulley 10, thence around pulley 28, thence around pulley 15, thence back to pulley 25, and around said pulley, and finally back to the bottom of pulley 10. It will be observed from the foregoing that a portion of clothesline 20 marked 20a in the drawing runs parallel to the front of the window frame 13. The full length of portion 20a is therefore accessible to a person standing at the inside of said window and it is a relatively easy matter to hang clothes on said portion 20a of the clothesline 20. It is not necessary hanging clothes on this portion of the clothesline to lean out of the window to reach it. It is easily accessible to a person standing inside a window and merely extending her hands outwardly through the window.

The clothes are hung on the lower portion of section 20a. This lower portion may be seen in Fig. 4 as engaging clothesline pulley 25.

It will be seen in Fig. 2 that clothes hung on section 20a of the clothesline must necessarily pass pulley 25 before they can reach the main portion of line 20 which extends between pulleys 25 and 15. Such being the case, it is necessary that provision be made in pulley 25 to clear the clothespins on said clothesline, as well as those portions of the clothes which are clamped between the clothespin and the clothesline. Such provision is made in pulley 25, as will clearly be seen in Figs. 3 and 4. It will be noted that pulley 25 has a scalloped peripheral edge and that the valleys in said edge extend substantially the full depth of the peripheral groove formed in said pulley in which the clothesline rides. The dimensions of each valley are such that it is adapted to accommodate a conventional clothespin 30, such as is depicted in Fig. 5, together with the clamped portion of the clothes which it supports. The raised portions of said scalloped edge are rounded so that should any clothespin be brought into engagement therewith, it would immediately slip into the adjacent valley.

It will be understood that when section 20a of the clothesline is loaded with wet wash, that said section of the clothesline and more particularly its lower portion will sag between the two pulleys 25 and 10. It will also be understood that when that section of the clothesline which extends between pulley 25 and pulley 15 is loaded with wash, that section, too, will sag. The problem of maintaining said clothesline, therefore, in uninterrupted engagement with pulley 25 is solved by the construction of the lower flange 31 of said pulley as shown in Fig. 4. It will be noted that said lower flange 31 slopes downwardly and it is therefore adapted to scoop up the sagging clothesline from either direction. The sloping flange 31 serves as a wedge which eases the sagging clothesline into the groove of the pulley.

Bracket 26 is of novel design and construction. It comprises a vertically extending portion 35 which is affixed by means of screws 36 to the window frame 27. It has a pair of horizontal portions 38 and 39, respectively, which are spaced from each other at a predetermined distance and which are affixed at one end to said upright member 35 and at their opposite end to a second upright member 40. The lower end of member 40 is bent inwardly and in the direction of portion 35, said lower end of portion 40 being disposed on a substantially horizontal plane parallel to the planes of portions 38 and 39. The space between portions 38 and 39 accommodates pulley

28 which is of conventional design. This pulley rides on a pin 45 which is vertically disposed and which extends through slots 46 and 47 in portions 38 and 39. It is by virtue of these slots that pin 45 is adapted to move in either direction longitudinally of members 38 and 39. Pin 45 is threaded at its upper end and a wing nut 50 is used to lock said pin in place on portions 38 and 39 of the bracket.

It will be noted in Fig. 4 that portion 38 of the bracket has an upwardly extending pin 51 formed thereon, and the lower portion 39 of the bracket has a downwardly extending pin 52 formed thereon. Tension springs 53 engage at one end pins 51 and 52, and at their opposite end pin 45. These tension members tend to hold pulley 28 in tensioned resistance to the pull of the clothesline upon it.

The construction last-mentioned described in connection with the mounting of pulley 28 on bracket 26 is intended for adjustment purposes to adjust the clothesline system as to the degree of tautness of the clothesline on the pulleys and to compensate for a stretched condition of the clothesline. In other words, this is an adjusting mechanism by which pulley 28 may be moved to tighten or loosen the clothesline on the pulleys.

Pulley 25 is mounted on a fixed pin 55 which is supported by portions 39 and 40 of the bracket 26. A sleeve spacer 56 prevents axial movement of said pulley 25 on said pin 55, and it adequately spaces said pulley from pulley 28 so that the distance between the grooves on said pulleys 28 and 25 corresponds to the diameter of the grooved portion of pulley 10. The upper and lower sections of clothesline portion 20a will thereby remain parallel to each other under normal conditions, that is, in the absence of a weight applied to the lower section of said clothesline portion.

In Fig. 5 a modified version of the scalloped pulley shown in Figs. 3 and 4 is shown. Here pulley 60 is a cast unit in which downwardly extending flange or lip 61 corresponds to the downwardly extending flange 31 of pulley 25. In the case of pulley 60, however, groove 62 is of substantially trough shape when viewed on the plane shown in Fig. 5. In other words, when said pulley lies on a horizontal plane, its peripheral line receiving groove defines a trough having a bottom wall and two side walls curving upwardly therefrom. This construction is designed to anchor the clothesline in place on said pulley 60 once its downwardly sloping lips 61 wedge said clothesline upwardly into groove 62 formed in said pulley. Once the clothesline is brought into engagement with said trough-like groove 62, there is very little likelihood that it will disengage said pulley when a heavy load on said line causes it to sag.

The foregoing describes preferred embodiments of this invention, and it will be appreciated that these embodiments are intended to illustrate rather than limit the scope and coverage of this invention.

I claim:

1. A clothesline and support therefor to be associated with a window opening which comprises a pair of brackets disposed at about the same level on opposite sides of the window opening, a pulley with a horizontal axis rotatably supported on one bracket and a pair of pulleys with vertical axes rotatably mounted one above the other on the other bracket, and a fourth pulley with a horizontal axis rotatably supported at a point distant from the superposed pulleys, an endless clothes-

line both runs of which pass around the pulleys with horizontal axes, the upper run of the line passing around the upper of the pair of superposed pulleys, the lower run of the line passing around the lower of said pair of pulleys, the bracket supporting the pair of superposed pulleys having a slot therein, the upper pulley of the pair having an axle pin riding in said slot, means for tightening said pin in said slot, and a pair of springs on the bracket and connected to opposite ends of said pin to exert resilient pull on said pin and its pulley.

2. A clothesline and support therefor to be associated with a window opening which comprises a pair of brackets disposed at about the same level on opposite sides of the window opening, a pulley with a horizontal axis rotatably supported on one bracket and a pair of pulleys with vertical axes rotatably mounted one above the other on the other bracket, and a fourth pulley with horizontal axis rotatably supported at a point distant from the superposed pulleys, an endless clothesline both runs of which pass around the pulleys with horizontal axes, the upper run of the line passing around the upper of the pair of superposed pulleys, the lower run of the line passing around the lower of said pair of pulleys, the lower pulley of said pair having flanges with scalloped peripheries to permit clothes pins on the line to pass around the pulley, said lower pulley spaced from the adjacent window opening of the building to permit clothes to be hung on the line passing across said opening, means for adjusting the position on the bracket of the upper pulley of the pair of superposed pulleys and means for locking it in any adjusted position.

3. A clothesline and support therefor to be associated with a window opening which comprises a pair of brackets disposed at about the same level on opposite sides of the window opening, a pulley with a horizontal axis rotatably sup-

ported on one bracket and a pair of pulleys with vertical axes rotatably mounted one above the other on the other bracket, and a fourth pulley with a horizontal axis rotatably supported at a point distant from the superposed pulleys, an endless clothesline both runs of which pass around the pulleys with horizontal axes, the upper run of the line passing around the upper of the pair of superposed pulleys, the lower run of the line passing around the lower of said pair of pulleys, the lower pulley of said pair having flanges with scalloped peripheries to permit clothes pins on the line to pass around the pulley, said lower pulley being horizontally spaced from the adjacent opening of the window frame to permit clothes to be hung on the line passing across said opening, the bracket supporting the pair of superposed pulleys having a slot therein, the axle pin of the upper pulley of the pair riding in said slot, means for tightening said pin in said slot, and a pair of springs on the bracket and connected to opposite ends of said pin to exert resilient pull on said pin and its pulley.
